UNITED STATES PATENT OFFICE.

LOUIS WILPUTTE, OF NEW YORK, N. Y.

COKE-OVEN.

1,212,865.

Specification of Letters Patent. Patented Jan. 16, 1917.

Application filed July 31, 1912. Serial No. 712,377.

To all whom it may concern:

Be it known that I, LOUIS WILPUTTE, a subject of the King of Great Britain and Ireland, residing in the borough of Manhattan, city, county, and State of New York, have invented certain new and useful Improvements in Coke-Ovens, of which the following is a specification.

My invention relates to regenerative coke-ovens, and has for its object, among other things, the construction of ovens and accompanying parts so as to insure the exact amount of air entering each flue for combustion with the gas; also to control the quantity of products of combustion for each regenerator, and to combine the parts comprising my oven in the simplest and most advantageous manner possible.

I will now describe my invention with reference to the accompanying drawings in which—

Figure 1 is a diagrammatic plan view of a coke-oven embodying my improvements; Fig. 2 is an enlarged longitudinal sectional view of a portion of the furnace, the section being taken on the line 2—2 in Fig. 3 looking in the direction of the arrow; Fig. 3 is a cross-sectional view on a reduced scale, the section being taken on the line 3—3 in Fig. 2; Fig. 4 is a similar view of a portion of the oven, the section being taken on a line 4—4 in Fig. 2 looking in the direction of the arrow; Fig. 5 is an enlarged longitudinal sectional detail view of a nozzle-brick employed in my device.

Similar numerals refer to similar parts throughout the several figures.

My improved coke-oven comprises a series of chambers 1 which are to contain the material to be transformed into coke, such material being placed in such chambers through openings 2 in the top thereof or other suitable passages. Between the chambers 1 are located heating chambers or flues 3 separated by partition walls 4 placed in communication with one another at their upper ends by openings 5. Since the openings 5 of each series of heating flues 3 are in alinement, they form a continuous passage way 6 for the gases as shown in Fig. 3.

By referring to Fig. 3, it will be seen that my coke-oven as a whole is divided into two communicating parts or sections by means of a wall 7, said two sections being indicated at 8 and 9. Each heating flue 3

has in communication therewith a regenerating chamber 10, said chambers having placed therein in this instance baffling plates 11 perforated at 12 through which perforations the air or mixed gases may flow, depending upon which series of air pipes 13 or 14 shown in Fig. 1 are open.

The air pipes 13 and 14 are connected together by a line pipe 15 which in turn is connected by a second line pipe 15^a to a fan or blower 16. The pipes 13 and 14 are each provided with a valve 17 and 17^a respectively, which control the flow of air through the pipes 13 and 14. Air from the blower 16 is forced, either through the pipe 13 or 14 into pipes 18, shown in Fig. 2, located beneath the regenerators 10 and between same, that is to say, there will be one pipe 18 for each pair of regenerators 10. The pipes 18 are connected to the line pipes 13 and 14 by branch pipes 19, shown in Fig. 1. The ends 20 of the pipes 13 and 14 are preferably sealed. Beneath the regenerators 10 are located the chambers 21, shown in Figs. 2 and 3 which are connected by branch pipes 22 (Fig. 1) to flues 23 leading into a chimney 24. The flues 23 are each provided with a gate valve 25, 25^a.

As illustrated in Fig. 2, the pipes 18 in this instance, are located in the channels 26 in the walls 27, and each of said pipes 18 is provided with nipples 28 directed toward the openings 29 in the walls 27, as shown in Fig. 3, which convey the air, as it passes from the nipples 28, into the regenerators 10.

The size of the openings in the nipples 28 upon the pipes 18 may be varied so as to control the admission of air to each separate generator in accordance with the requirements of combustion, as will be readily understood by those skilled in this art.

Each regenerator 10 is placed in communication with its particular heating flue 3 by a passage 30 arranged in the horizontal table member 31 of the coke-oven proper, as is shown in Figs. 2 and 3. Each heating flue 3 in each particular section of the oven is connected with a gas duct 32 through a port 33, there being a separate port 33 for each heating flue 3. Between the gas duct and each port 33 I interpose a removable nozzle 34 which preferably consists of a cylindrical brick somewhat tapered at the ends and provided with a relatively small opening 35, as shown in Fig. 5, which alines

with a larger opening or passage 36 in the top wall of the masonry or brick construction 37 which contains the gas duct 32.

As is shown in Fig. 2, there is an independent gas duct 32 for each set of heating flues 3, and by referring to Fig. 4, it will be seen that each gas duct 32 stops short of the partition wall 7, whereby each section of my improved coke-oven is independently heated. By referring again to Fig. 4, it will be seen that there is a separate nozzle 34 for each heating flue 3. These nozzles 34 simply rest in the recess 38 formed in the top wall 37 for approximately one-half their diameter as shown in Fig. 5, the upper half of the nozzles 34 projecting into a recess 39 in the table member 31. Gas may be conducted to the ducts 32 in any suitable manner as by pipes 42^a for example.

During the operation of my improved coke-oven air will flow through the pipes 13 and 14 alternately, and the gases will flow through the flues 23 in a correspondingly alternate manner into the chimney 24, according to the wishes of the operator. The usual operation continues, about one-half hour in one direction and then the reverse is employed. In other words, when the material to be coked is placed in the chambers 1 combustion will be produced in section 8 for example, at which time air will flow through the pipe 13, the valve 17^a in the line 14 being closed, and then gas will be caused to flow into the ducts 32 in said section 8. The mixture of air and gas will now burn in the heating flues 3 in said section 8. While combustion is taking place in section 8, the flue 23 adjacent to section 9 will carry off the hot gases to the chimney 24, the gate valve 25^a being closed. The hot gases from section 8 will pass over the partition wall 7 down through the flues 3 and regenerators 10 into section 9 and into the flue 23 adjacent thereto. The mixture in section 8 will be allowed to burn for a certain time, say one-half hour, as heretofore set forth, at the expiration of which, air will be shut off from pipe 13 and forced into pipe 14 by means of the valves 17 and 17^a and simultaneously the gate valve 25^a will be opened and the gate valve 25 closed. When this has been accomplished, the mixture of air and gas will be burned in section 9, and will afterward flow through section 8; in other words, the operation will be reversed, and the air passing into section 9 will pass through the heated regenerator 10 of section 9, said regenerators having already become heated from the passage of the hot gases from section 8.

In the apparatus disclosed herein the distribution of the air supplied to any one of the groups of flues 3 connected by a single channel 6 and lying at one side of the division wall 7, depends upon the relative pro-

portions of the corresponding nozzles 28, while the distribution among the flues of the same group of the gases descending therethrough, when the direction of flow through the flues is reversed, depends upon the proportions and arrangements of the paths traversed by the streams descending through the flues and is independent of the nozzles 28 by which air is supplied to these flues.

The claims of the present application are restricted to the form of apparatus shown wherein the provision of an individual regenerator for, and connected to each heating flue, with an individual air inlet for each regenerator separate from the waste gas outlet connection thereto, is an essential characteristic of the particular means employed to make the distribution of air supplied to the different flues of a group independent of the reverse flow through the same flues.

In my co-pending application, Serial No. 763,714, filed April 26th, 1913, I have disclosed and have claimed the common features of novelty found in the form of apparatus disclosed herein, and other forms of apparatus in which the distribution of flow in one direction among the different flues of a group is made independent of the distribution of flow in the opposite direction through the same flues without the employment of an individual regenerator for each heating flue.

The construction of my improved coke-oven, as herein shown and described, is merely for the purposes of illustrating the principle and method of carrying out my invention. In practice it will be formed of brick or other suitable materials and may be somewhat varied from the construction here shown.

What I claim is:—

1. A coke oven structure comprising coking chambers with a plurality of heating flues, a plurality of regenerators one individual to and connected to one end of each of said flues, said flues being arranged in sets each comprising a plurality of flues connected together at their ends remote from those to which the regenerators are connected and means for maintaining a flow alternately in opposite directions through said flues and regenerators comprising outlet connections to the regenerators for conveying waste gas away from the latter, and air supply connections to the regenerators including a separate air inlet for each regenerator.

2. A coke oven structure comprising coking chambers with a plurality of heating flues, a plurality of regenerators one individual to and connected to one end of each of said flues, said flues being arranged in sets each comprising a plurality of flues connected together at their ends remote from those to which the regenerators are connected and

- means for maintaining a flow alternately in opposite directions through said flues and regenerators comprising outlet connections to the regenerators for conveying waste gas away from the latter, air supply connections to the regenerators including a separate air inlet for each regenerator, and means for supplying air in proportional amounts to the air inlets of the separate regenerators.
- 10 3. A coke oven structure comprising coking chambers with a plurality of heating flues, a plurality of regenerators one individual to and connected to one end of each of said flues, said flues being arranged in sets each comprising a plurality of flues connected together at their ends remote from those to which the regenerators are connected and means for maintaining a flow alternately in opposite directions through said flues and regenerators comprising outlet connections to the regenerators for conveying waste gas away from the latter, air supply connections to the regenerators including a separate air inlet for each regenerator, and combustible gas supply connections including a separate gas supply nozzle for each flue.
- 15 4. A coke oven structure comprising coking chambers with a plurality of heating flues, a plurality of regenerators one individual to and connected to one end of each of said flues, said flues being arranged in sets each comprising a plurality of flues connected together at their ends remote from those to which the regenerators are connected and means for maintaining a flow alternately in opposite directions through said flues and regenerators comprising outlet connections to the regenerators for conveying waste gas away from the latter, air supply connections to the regenerators including a separate air inlet for each regenerator, and combustible gas supply connections including a separate gas supply nozzle for each flue.
